US0D1068831S

(12) **United States Design Patent** (10) Patent No.: **US D1,068,831 S**
(45) Date of Patent: ** Apr. 1, 2025

(54) **ELECTRONIC DEVICE WITH GRAPHICAL USER INTERFACE**

(71) Applicant: **Realsee (Beijing) Technology Co., LTD.**, Beijing (CN)

(72) Inventor: **Hua Yang**, Beijing (CN)

(73) Assignee: **Realsee (Beijing) Technology Co., LTD.**, Beijing (CN)

(**) Term: **15 Years**

(21) Appl. No.: **29/894,312**

(22) Filed: **Jun. 8, 2023**

Related U.S. Application Data

(63) Continuation of application No. 35/515,475, filed on Aug. 29, 2022 (U.S. filing date under 35 U.S.C. 384), and having an international filing date of Aug. 29, 2022.

CLAIM

The ornamental design for an electronic device with graphical user interface as shown and described.

DESCRIPTION

The FIGURE is a front view of an electronic device with graphical user interface showing the claimed design. The outer perimeter shown in broken lines illustrates an electronic device and forms no part of the claimed design; the remaining broken lines in the FIGURE illustrate portions of the graphical user interface that form no part of the claimed design.

1 Claim, 1 Drawing Sheet
